His Attorney

UNITED STATES PATENT OFFICE.

CLARENCE S. SNAVELY, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

ELECTRIC RELAY.

Application filed October 24, 1923. Serial No. 670,447.

To all whom it may concern:

Be it known that I, CLARENCE S. SNAVELY, a citizen of the United States, residing at Pittsburgh, in the county of Allegheny

5 and State of Pennsylvania, have invented certain new and useful Improvements in Electric Relays, of which the following is a specification.

10 My invention relates to electric relays, and particularly to contact mechanism for relays.

15 I will describe two forms of relay contact mechanism embodying my invention, and will then point out the novel features there- of in claims.

20 In the accompanying drawings, Fig. 1 is a view showing, in front elevation, a relay having one form of contact mechanism embodying my invention. Fig. 2 is a view showing a modification of the contact mechanism of Fig. 1 and also embodying my invention. Fig. 3 is a view showing the contact mechanism of Fig. 2 as viewed from the left.

25 Similar reference characters refer to similar parts in each of the views.

Referring first to Fig. 1, the reference character A designates the base plate of a relay. This plate A is of some suitable insulating material such as porcelain and carries an electromagnet B. The core 1 of this magnet passes through the plate A and terminates, on the under side of the plate, in a pole face 2. Secured to the side of pole 35 face 2 by means of a screw 4 is a bracket 3. An armature 6 of suitable magnetizable material such as soft iron is pivotally supported at point 5 by bracket 3 and is arranged to be drawn upward toward pole face 2 when magnet B is energized. Attached to this armature 6 by means of insulating studs 7 is a contact arm C secured to the studs by means of nuts 7^a. The left hand end of this arm is bent upward at an

40 angle with the body of the arm and the tip of this bent portion is offset to form the lower leg 12 of a yoke. The other leg 13 of this yoke is fastened to leg 12 by means of rivets 17. Interposed between these two 45 legs 12 and 13 and extending outwardly therebetween is a flexible conducting spring contact finger 14 provided at its upper ex-

tremity with a low resistance contact tip 16 of some suitable material such as silver, which tip co-acts with a fixed contact member 11.

When magnet B is de-energized, contact arm C drops down against stop 23 under the influence of gravity, but when this magnet is energized the arm C swings upward till armature 6 strikes pin 21 in pole face 2. During this motion contact finger 14 engages the fixed contact member 11.

If arm C is in its lower position and magnet B becomes energized, armature 6 is moved upward but the force exerted by the magnet increases as the armature approaches the pole face. Soon after this motion commences, finger 14 engages contact 65

11 and thereafter arm 14 is flexed or bent, thus increasing the pressure of contact and decreasing, therefore, the electrical resistance of the contact. It is desirable to make this pressure as heavy as possible for a given energization of magnet B. If spring 70 finger 14 is too stiff, the force exerted by magnet B will not be sufficient to complete the stroke of armature 6. If, on the other hand, the spring finger 14 is sufficiently weak to permit the armature 6 to complete 75

its stroke, the pressure exerted by the spring at full stroke is much less than the force exerted by the magnet since the pressure exerted by finger 14 is directly proportional to the deformation in this member and 80 hence to the motion of armature 6, whereas the force exerted by magnet B increases inversely as the distance between the pole face and the armature according to some function of this distance greater than unity. 85

It is therefore plain that to gain the maximum of advantage from the pull exerted by the actuating magnet, the stiffness of spring finger 14 should be progressively increased as the armature moves through its 90 stroke. One method of accomplishing this result is shown in the drawing in which a plurality of screws 18, 19 and 20 are adjustably inserted in leg 12 to engage the back of finger 14 during the operation of 95

the contact. As the armature moves upward, finger 14 engages first screw 20, then screw 19, and finally, just before the end of the stroke, screw 18. It will be plain that 100

the location of the point of maximum bending movement is thus progressively moved toward the tip of the finger 14 and hence the resistance of this finger to bending is increased in accordance with increases in the force exerted by magnet B. It is clear that at the instant tip 16 engages contact 11, magnet B is exerting a certain force upon the armature. The bending stress of finger 14 when the contact is open is adjusted, by means of screw 15, threaded in top leg 13, so that the force required to bend the finger away from the screw will be slightly less than that exerted by magnet B at the instant of contact.

Referring now to Figs. 2 and 3, in the mechanism here shown, the screw 15 of Fig. 1 is replaced by a downwardly projecting end 13^a of top leg 13 which engages the upper surface of finger 14 for the purpose explained hereinbefore. In place of screws 18, 19 and 20, the lower leg 12 of arm C is of accurate form and has its right hand end in contact with the lower side of spring finger 14. As the finger 14 is flexed downward it rolls along the shank of leg 12 and thereby constantly changes the resistance offered by finger 14 to flexure of the finger.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination, an electromagnet, an armature controlled thereby, a fixed contact member, a spring contact finger moved into engagement with said member by said armature when the magnet becomes energized, whereby the force exerted on said finger increases as the armature approaches the magnet, the parts being so arranged that the finger engages the member before the motion of the armature is completed, and means for progressively increasing the stiffness of said finger from the time the finger engages the fixed member to the time the motion of the armature is completed.

2. In combination, an electromagnet, an armature controlled thereby, a fixed contact member, a spring contact finger moved into engagement with said member by said armature when the magnet becomes energized, whereby the force exerted on said finger increases as the armature approaches the magnet, the parts being so arranged that the finger engages the member before the motion of the armature is completed, and means for progressively decreasing the effective length of said finger from the time the finger engages the fixed member to the time the motion of the armature is completed.

In testimony whereof I affix my signature.

CLARENCE S. SNAVELY.
